UNITED STATES PATENT OFFICE.

CHRISTIAN G. FEUCHT, OF BROOKLYN, NEW YORK.

CAR COUPLING.

Application filed June 3, 1922. Serial No. 565,541.

To all whom it may concern:

Be it known that I, CHRISTIAN G. FEUCHT, a citizen of the United States, and resident of Brooklyn, in the county of Kings and State of New York, have invented certain new and useful Improvements in Car Couplings, of which the following is a specification.

The present invention relates to car couplings and is designed more particularly for roller coasters in which a plurality of cars are coupled together and elevated up an inclined track by a carrier chain, and then run by gravity over numerous dips, rises and curves, causing upon the cars a wide range of rapid angular movements which are transmitted to the couplings.

The general object of the invention is to provide a resilient coupling adapted to absorb both the compressive and tensional shocks occasioned by the movements of the cars, and to yieldingly co-operate with the carrier chain of the inclined track section to effect an equal driving action upon the several connected cars.

A further object is to provide lubricating means for the several parts of the coupling and to protect the same against dust or damage by means of a suitable casing.

The objects also include a coupling having its opposite ends similarly constructed whereby, in coupling up, the ends may be reversed within the coupling heads and still retain a proper coupled position; the construction also includes means, in case of disconnection or breakage at one end, for supporting the coupling in such a manner as to prevent the free end from falling upon the track and tending to derail the cars.

For further comprehension of the invention, and of the objects and advantages thereof, reference is had to the following description and accompanying drawings, and to the appended claims in which the various features of the invention are more particularly pointed out.

Figure 1 of the drawings is an exterior plan view of the coupling constructed in accordance with the present invention.

Figure 2 is a side view shown partially in section.

Figure 3 is a side elevation of a plurality of cars coupled together and shown in connection with a carrier chain.

As shown in the drawings numeral 10

represents the base of the coupling heads arranged to be conveniently secured to the ends of the cars, indicated by the lines 10^a, the heads being provided with the jaws 11, perforated to receive the coupling pins 12. Hingedly mounted at one end between the jaws 11 by the pins 12 are the coupling links 13, the opposite end of which is slotted or grooved in a manner to form the two side walls 14, arranged to receive the tongue 15 of the coupling ends 16 and 17, the tongues being hingedly connected to the side walls by the pins 18. At their joint ends the connected coupling links 13 and tongues 14 slidably engage each other and form bearing faces 20 and 20^a arranged to receive in part the compressive thrusts on the coupling for the partial relief of the pins 18. At the faces 20^a, the coupling ends 16 and 17 laterally project on either side of their tongues 15 and form a clearance space with respect to the opposite beveled ledges 21 formed on the links 13 and permit a limited degree of pivotal movement about their pivotal connection 18.

The coupling end 16 is provided with a reduced portion 22, having threaded engagement with the interior of the tubular member 23, the larger diameter of the coupling end being also in threaded engagement with the interior of the outer casing 24, the reduction of the coupling end forming a shoulder or abutment on the latter adapted to receive the thrust of one end of the spring 25. Also the coupling end 17 is reduced to form a coupling rod 19 which extends in slidable engagement into the tubular member 23; a collar 26 slidably surrounds the latter and is fixed to the rod 19 by the pin 27, preferably formed oblong in cross section, with its longer dimension alined with the axis of the rod to maintain sufficient strength thereof, slots 28 being provided in the opposite side walls of the tubular member which loosely receives the pin and permits a limited rotary movement between the tubular member and the rod. To the free end of the tubular member 23 is fixed in threaded relation a bush 29 which surrounds the rod 19 and with respect thereto is provided with an annular chamber or recess to receive the packing ring 30, preferably of felt material. The inner end of the bush serves as an abutment for the spring 31, while its outer surface closely engages the outer end of the casing 24. Pin

holes 32 are provided for the bush 29, and by means of a suitable pin wrench the bush may readily be removed for the renewal of the packing 30, and the introduction of a lubricant into the casing.

The two springs 25 and 31 are proportioned to absorb the shock and resist the compressive and tensional forces due to the movements of the cars, the former force being transmitted by the inward movement of the rod 19 and collar 26, which compresses the spring 25 against the shoulder formed on the coupling end 16, and the latter or tensional force by the outward movement of the rod and collar acting to compress the spring 31 against the bush 29.

As thus provided with the outer casing 24, the resilient parts are fully protected against dust and damage and the casing also serves as a container for the necessary lubricant which works its way around the springs and through the slots 28 and over the surfaces of the several sliding parts. Furthermore the outer casing as thus centrally spaced with and connected at opposite ends to the tubular member 23 jointly operates therewith to more effectively resist the lateral thrusts from the moving cars.

By means of the double hinge connections of the coupling links 13 and coupling ends 16 and 17, together with the limited rotary movement between the coupling rod and tubular member afforded by the clearance of the elongated slot of the latter, the coupling may assume the universal angular positions required for the movement of the cars over the various dips, rises and curved track sections, and in the event of an accidental disconnection or breakage at one end of the coupling, the loose end thereof is supported by the opposite coupling end in its engagement with the beveled ledges 21 formed on the edges of the side walls 14. As thus supported the loose end of the disconnected coupling is prevented from falling upon the track and tending to derail the cars.

As shown in Fig. 3, the carrier chain 32 acting through the dogs 33 is adapted to exert an equal driving action upon the several cars by the yielding action of the coupling 24 which allows the weight of a car or its running resistance to be transmitted through its dog to the adjacent carrier link.

Also, in the similar construction of the opposite ends of the coupling, means are provided whereby in coupling up by the pins 12 either end of the coupling may be inserted in either of the heads, or the coupling may be turned about its axis and either of its opposite sides inserted, thus affording means for more readily accomplishing the coupling operation with little or no attention.

While I have shown and described the preferred construction and arrangement of

the coupling, it is to be understood that detail changes may be made therein without departing from the general principle of the invention.

Having thus described by invention, what I claim and desire to secure by Letters Patent, is:

1. In a car coupling, an outer casing provided at one end with a car connection, a tubular member disposed in spaced relation within said casing and secured at one end to the car connection thereof and arranged to form a spring abutment thereon, means provided at the opposite or free end of said tubular member for engaging the inner wall of said casing and forming a spring abutment, a coupling rod having an end longitudinally slideable in said tubular member and provided at its opposite end with a car connection, a collar slidably mounted on said tubular member and connected through the walls of the latter in fixed relation with said coupling rod, and helical springs mounted upon said tubular member on opposite sides of said collar and disposed to engage said abutments and exert an endwise resistance in opposite directions to the movement of said rod. 75 80 85 90

2. In a car coupling, an outer casing provided at one end with a car connection, a tubular member disposed in spaced relation within said casing and secured at one end to the car connection thereof and arranged to form a spring abutment thereon, a bush detachably secured to the opposite or free end of said tubular member for engagement with the inner wall of said casing and forming a spring abutment, a coupling rod having an end longitudinally slideable in said tubular member and provided at its opposite end with a car connection, a collar slidably mounted on said tubular member and connected through the walls of the latter in fixed relation with said coupling rod, and helical springs mounted upon said tubular member on opposite sides of said collar and disposed to engage said abutments and exert an endwise resistance in opposite directions to the movement of said rod. 95 100 105 110 115

3. A car coupling comprising a coupling end provided with a reduced end portion and forming therewith a shoulder or abutment, a tubular member threaded at one end to the reduced portion of said coupling end, a bush threaded to the opposite end of said tubular member and forming therewith an abutment, a coupling rod slideable through said bush and within said tubular member and having its outer end provided with a car connection, a collar slideable on said tubular member and fixed to said coupling rod by a pin extending through and movable in a slot formed in the walls of said tubular member, and springs disposed around said tubular member and between said collar and 120 125 130

the abutments at the ends of said tubular member.

4. A car coupling comprising a tubular member provided at one end with an enlarged portion forming a car connection and a spring abutment, said tubular member having slots extending through the opposite side walls thereof, a bush secured to the opposite end of said tubular member and forming therewith a spring abutment, a coupling rod slideable through said bush and within said tubular member and having its outer end provided with a car connection, a collar slideable on said tubular member and fixed to said coupling rod by a pin extending through and slideable within the slots formed in said tubular member, springs disposed around said tubular member and between said collar and the abutments at the ends of said tubular member, and a casing enclosing said springs, collar and tubular member, said casing being fixed at one end to the enlarged portion provided for the tubular member.
- 25 5. A car coupling comprising a tubular member provided at one end with a car connection, a coupling rod slideable within said tubular member and having its outer end provided with a car connection, a bush fixed to the opposite end of the tubular member and having a portion thereof surrounding the coupling rod and shaped with respect thereto to form an annular chamber for the reception of packing, and springs arranged upon said tubular member and adapted to resist the compressive and tensile stresses between said coupling rod and said tubular member.
- 40 6. In a car coupling, a casing provided at one end with a coupling connection, a tubular member mounted within said casing in spaced relation therewith and fixed to

the coupling connection, a bush adjustably mounted in the opposite or free end of said casing and secured to said tubular member, a coupling rod slideable at one end through said bush and within said tubular member and provided at its outer end with a coupling connection, a collar slideable in the space between said casing and tubular member and fixed to said coupling rod, and springs disposed within the space between said casing and tubular member and on opposite sides of said collar and adapted to exert an endwise resistance in opposite directions to the movement of said rod.

7. In a car coupling, a casing provided at one end with a coupling connection, a tubular member mounted within said casing in spaced relation therewith and detachably fixed to the coupling connection, a bush adjustably mounted in the opposite or free end of said casing and detachably secured to said tubular member, said latter member having its opposite side walls provided with elongated slots, a coupling rod slideable at one end through said bush and within said tubular member and provided at its opposite end with a coupling connection, a collar slideable in the space between said casing and tubular member and fixed to said coupling rod by a pin loosely extending through the elongated slots in the side walls of said tubular member, and springs disposed within the space between said casing and tubular member and on opposite sides of said collar and adapted to exert an endwise resistance in opposite directions to the movement of said rod.

Signed at Brooklyn, in the county of Kings and State of New York, this 29th day of May A. D. 1922.

CHRISTIAN G. FEUCHT.
